BY Chas B. Mann
ATTORNEY.

UNITED STATES PATENT OFFICE.

JOHN B. OLDERSHAW, OF BALTIMORE, MARYLAND.

AIR-HEATING STOVE.

SPECIFICATION forming part of Letters Patent No. 449,691, dated April 7, 1891.

Application filed July 26, 1890. Serial No. 359,993. (No model.)

To all whom it may concern:

Be it known that I, JOHN B. OLDERSHAW, a citizen of the United States, residing at Baltimore, in the State of Maryland, have invented certain new and useful Improvements in Air-Heating Stoves, of which the following is a specification.

This invention relates to an improved air-heating stove, which is illustrated in the accompanying drawings, in which—

Figure 1 is a side elevation of the stove. Fig. 2 is a vertical elevation of the same. Fig. 3 is a plan view of the stove as seen when the top is removed at the line 3 3. Fig. 15 4 is an inverted plan of the stove-top, that part above the line 3 3. Fig. 5 is an upper side view of the stove-top.

The object of this invention is to provide a heating-stove with such construction as will 20 increase its capacity to heat air.

The letter A designates the base, which may be of any design or pattern; B, the cylinder inclosing the combustion-chamber B', and C the grate.

25 The ash-receptacle D is in the base.

Within the walls of the cylinder and a little below the top thereof is a crown-sheet or fire-plate E, which forms the top of the combustion-chamber B' and also the bottom of a 30 hot-air chamber F, the top of which is formed by the plate G.

Above the top hot-air chamber F is a chamber H for gas and other products of combustion.

35 A direct smoke-flue I leads from the combustion-chamber B' up past the top air-chamber F to the gas-chamber H. A damper J is at the top of the said smoke-flue I and is shifted by means of a rod J', whereby the 40 smoke-flue may be opened and closed.

The top air-chamber F has a wall l at the front, which extends therefrom part way around at each side, and thereby forms two 45 indirect smoke-flues m, each at a side opposite the other, which lead up to the gas-chamber H. Openings m' are in the top plate G and register with the indirect smoke-flues m.

A semicircular shell or jacket K forms an air-chamber K', which incloses the back wall 50 of the cylinder B. The jacket of this back air-chamber forms a vertical front face n at each of two opposite sides of the cylinder B,

and at the bottom cold-air inlets o lead to the back chamber.

The top hot-air chamber F and the back 55 air-chamber K' are in communication by two side spaces p, which are between the direct smoke-flue I and the two indirect smoke-flues m.

A hot-air outlet q at the front part of the 60 hot-air-chamber F provides for the escape into the room of all the air that may be heated in either the back chamber K' or the top chamber F.

A smoke-pipe r leads from the gas-chamber 65 H at a point adjacent to the top of the direct smoke-flue I. Both the direct flue I and the indirect flues m carry smoke and gases from the combustion-chamber B' to the smoke-pipe r, and all of these flues lead to the gas- 70 chamber H. When the damper J is closed, all the products of combustion will escape by the side or indirect flue m, and thereby the front walls of the cylinder will be more intensely heated by the hot gases in the chamber B' before said gases pass to the top gas-chamber H. The gas-chamber H assists to 75 heat the room in the same manner that the front part of the cylinder B and exterior of jacket K do—by direct radiation.

A boiler-hole s is in the top plate of the gas-chamber back of the center of said chamber and immediately above the top of the direct smoke-flue I.

In the drawings an ornamental device t is 85 seated over the boiler-hole s. Upon removal of this a kettle or boiler may be placed over the hole, where the full effects of the heat will be obtained.

Having described my invention, I claim— 90

1. A cylinder-stove having a combustion-chamber B', having a crown-sheet E, a top gas-chamber H, a hot-air chamber F between the said crown-sheet and gas-chamber, a smoke-pipe r, leading from the back of the 95 gas-chamber, a back smoke-flue I, leading from the combustion-chamber direct to the said smoke-pipe, a damper to control this flue, and two side smoke-flues m from the combustion-chamber to the gas-chamber, as set forth. 100

2. A cylinder-stove having a combustion-chamber B', having a crown-sheet E, a top gas-chamber H, a hot-air chamber F between the said crown-sheet and gas-chamber, a

smoke-pipe *r*, leading from the back of the gas-chamber, a back smoke-flue *I*, leading from the combustion-chamber direct to the said smoke-pipe, a damper to control this flue, 5 and the top plate of the gas-chamber provided with a boiler-hole *s* back of the center of said chamber and immediately over the top of the said back smoke-flue.

3. The combination of a combustion-cylinder having a crown-sheet *E*, a top gas-chamber *H*, a hot-air chamber *F* between the crown-sheet and gas-chamber and provided with an

outlet *q*, and a semicircular jacket *K*, inclosing the back wall of the combustion-cylinder and forming there a hot-air chamber which 15 is in communication with the said hot-air chamber above the crown-sheet.

In testimony whereof I affix my signature in the presence of two witnesses.

JOHN B. OLDERSHAW.
